WRITING INSTRUMENT

Clarence D. Zierhut, Granada Hills, Calif., assignor to
Paper Mate Manufacturing Company, Santa Monica,
Calif., a corporation of Delaware

Filed Sept. 22, 1966, Ser. No. 3,964

Term of patent 14 years

(Cl. D74—17)

FIG. 1.

FIG. 2.

FIG. 1 is a front elevational view of a writing instrument showing my new design;

FIG. 2 is a top plan view thereof.

The characteristic features of my design reside in the provision on the specific writing instrument disclosed of a virtually median band and a pair of narrow bands connected by a concave annular recessed portion, the latter being located in a zone spaced from the rear end of the writing instrument a distance of about one-sixth the overall length, all as shown.

I claim:

The ornamental design for a writing instrument, as shown and described.
